UNITED STATES PATENT OFFICE.

ISAAC L. DELANEY, OF WAYNESBURG, PENNSYLVANIA.

ARTICLE-CONTROLLED VALVE MECHANISM.

1,199,967.

Specification of Letters Patent.

Patented Oct. 3, 1916.

Application filed July 26, 1915. Serial No. 41,849.

To all whom it may concern:

Be it known that I, ISAAC L. DELANEY, a citizen of the United States, residing at Waynesburg, in the county of Greene and State of Pennsylvania, have invented certain new and useful Improvements in Article-Controlled Valve Mechanism, of which the following is a specification.

This invention relates to improvements in stoves and furnaces, and more specifically to article-controlled valve mechanism for gas stoves.

The object of my invention is to provide an article-controlled valve mechanism that may be mounted upon the conventional type of gas cock used upon gas stoves with but very slight changes and additions, and at a relatively small cost. Means are provided whereby the placing of a cooking utensil over the burner of a stove provided with my device will operate to turn on the full flow of gas through the valve, whereas, the removal of the utensil will automatically operate to cut off all but a very small flow of gas. This tends greatly toward economy in fuel consumption.

Other objects of this invention not at this time more particularly enumerated, will be clearly understood from the detailed description and drawings forming a part of this specification.

Furthermore, this invention consists in the novel arrangement and combination of parts more particularly described in the following specification and embodied in the claims appended hereunto and forming a part of this application.

Referring now to the drawing, which is merely illustrative of my invention, the figure is a side elevation of my device, partly in section, shown in operative relationship with a burner, the open position being represented in dotted lines.

Referring further to the drawing, where in similar reference characters designate similar parts throughout the respective views, 1 designates an ordinary gas cock, provided with a transverse port 2, adapted to receive a fuel supply pipe (not shown), and a fuel regulator 3. The type of cock to which my device is particularly adaptable is provided with a boss 4, within which is an exhaust port 5. A T-joint 6 is adapted to be secured within the lower portion of said boss, said joint being provided with a fuel passageway 7 centrally therethrough. Said

passageway 7 is bored to a greater diameter at one end as at 7^a, while it terminates in a conical valve seat 7^b at the other end thereof. A valve stem 8, provided with a suitable packing 9 is adapted to be inserted in said passageway 7, said packing 9 being adapted to seat in the larger bore 7^a of said passageway. The inner extremity of said valve stem 8 is formed with a substantially conical end adapted to form a closure for said valve seat 7^b. Said conical end is formed with a flattened face (not shown) on one side thereof so that there will be a small aperture between the seat and the valve stem when said valve is entirely closed.

A burner 10 of any suitable construction is connected to the valve end of said T-joint.

A right-angularly shaped lever 11 is pivoted centrally of its shorter arm to the casting of said cock 1, as at 11' the free end of said short arm being secured upon one end of said valve stem 8. The longer arm of said lever 11 is provided with an offset portion 12 to which is secured one end of a leaf spring 13, the free end of which engages with the upper face of said cock. A rod 14 is secured near the free end of the longer arm of said bell-crank lever and is vertically disposed at right angles thereto. A button 15 is mounted upon the upper end of said rod which extends slightly above the level of the grating 16 of a stove and is adapted to be depressed by a cooking utensil placed thereon.

From the foregoing description it is obvious that when a cooking utensil is placed upon the grating 16 of a stove equipped with my device, the longer arm of the lever will be depressed thereby pulling the shorter arm thereof forward. This will operate the valve stem 8, thereby opening the valve at 7^b. At all times the port 2 is filled with gas and the flow of the fuel is primarily regulated by the fuel regulator 3. When the vessel is removed from the grating 16 the spring actuated lever will automatically close the valve at 7^b, thereby cutting off the flow of gas, excepting that which is permitted to escape through the aperture between the valve seat and the valve stem, whereby the gas flame is kept burning in the burner, though with a very small blaze.

The utility, adaptability, and advantages of my improved form of article-controlled valve mechanism for gas stoves being obvi-

ous, it is unnecessary to further enlarge upon the same herein.

Having now described and pointed out the new and useful features of my invention, I 5 do not limit myself to the shape of certain parts where the shape is not essential, nor do I restrict myself to the exact details of construction shown and described, but mean and intend to claim all equivalents and 10 variations thereof not departing in principle from my invention, and falling within the purview of the appended claims.

What I claim as my invention and desire to secure by Letters Patent is:

15 1. In an article-controlled valve for stoves, the combination of a main supply conduit having an outlet duct, a T-joint connected thereto and having a duct communicating with first said duct, a needle valve in one of 20 the arms of said T-joint to close communication therethrough, a right-angular lever

pivoted on said supply conduit and having an arm thereof connected with the needle valve, and article engaging means carried by the free end of said lever.

2. In an article controlled valve for stoves, the combination of a main supply conduit having an outlet duct, a T-joint connected thereto and having a bore communicating with said duct, a needle valve in said T-joint, a right-angularly engaged lever pivoted on said supply conduit and having the shorter arm thereof connected with the needle valve, spring means carried by the longer arm to engage the supply conduit and return the lever to normal position after an actuation, the free end of said lever being adapted to engage objects.

In testimony whereof I affix my signature hereto.

ISAAC L. DELANEY.
